UNITED STATES PATENT OFFICE.

ISIDORE RESSLER, OF DETROIT, MICHIGAN.

DISINFECTANT-PAD.

1,265,957.

Specification of Letters Patent. Patented May 14, 1918.

Application filed October 9, 1916. Serial No. 124,511.

To all whom it may concern:

Be it known that I, ISIDORE RESSLER, a subject of the King of England, residing at Detroit, in the county of Wayne and State of Michigan, have invented certain new and useful Improvements in Disinfectant-Pads, of which the following is a specification, reference being had therein to the accompanying drawings.

- 10 This invention relates to a disinfecting tablet or pad whereby a disinfectant may be readily placed at any desired point in a sick ward, school room, public meeting hall or the like and furnish a continuous supply 15 of disinfectant by evaporation or vaporization, the device being so arranged that it is readily attached to any support and efficiently performs its work without attention. The device also includes a distribution of 20 disinfecting material so as to present a very large surface for volatilization into the atmosphere.

The invention consists in the matters hereinafter set forth, and more particularly 25 pointed out in the appended claim.

In the drawings,

Figure 1 is a view in perspective of a device embodying features of the invention, and

- 30 Fig. 2 is a view in longitudinal section therethrough.

As herein shown a holder in the form of a sheet 1 of pasteboard, sheet metal or other preferred material, that is perforated as at 2 for ready support on a pin, tack or the like, has a body of medicament 3 applied to the lower portion thereof so as to completely envelop and surround both faces and pro-

duce a body having a very large area. It is to be understood that the medicament is in 40 the form of a volatile disinfectant or deodorizer and may be of any preferred ingredients to produce the desired result.

As a result of this construction, a disinfecting pad is provided that is unobtrusive 45 in appearance, that may be placed at any local point in a sick room, hospital ward or the like, that may be multiplied as desired to cover or control distribution of the disinfectant over the desired area or in any place, 50 and that requires no attention.

Obviously, changes in the details of construction may be made without departing from the spirit of my invention but I do not care to limit myself to any particular 55 form or arrangement of parts.

What I claim is:-

A disinfectant pad, comprising a pasteboard sheet coated on each side for the major portion of its length with a comparatively thick body formed of a composition capable of slowly volatilizing to give off antiseptic and disinfecting effluvia, the material completely enveloping the included portion of the pasteboard and presenting a 65 maximum surface for contact with the atmosphere, the protruding portion of the pasteboard being arranged as a hanger for suspending the pad.

In testimony whereof I affix my signature 70 in the presence of two witnesses.

ISIDORE RESSLER.
